Primary Examiner — T Chase Nelson*Assistant Examiner* — Jonathan J Han(74) Attorney, Agent, or Firm — Warshaw Burstein, LLP;
John Laurence(57) CLAIM

The ornamental design for a footwear, as shown and described.

DESCRIPTION

FIG. 1 is a front right perspective view of the footwear;
FIG. 2 is a front left perspective view of the footwear;
FIG. 3 is a top view of the footgear;
FIG. 4 is a bottom view of the footwear;
FIG. 5 is a front view of the footwear;
FIG. 6 is a back view of the footwear;
FIG. 7 is a right-side view of the footgear; and,
FIG. 8 is a left-side view of the footwear.
The broken lines in the figures show portions of the footwear that form no part of the claimed design.

1 Claim, 4 Drawing Sheets(56)
